CLAIM

The ornamental design for a fitness tracker as shown and described.

DESCRIPTION

FIG. 1 is a top side isometric view of a body of a fitness tracker.

FIG. 2 is a bottom side isometric view thereof.

FIG. 3 is a front side elevation view thereof.

FIG. 4 is a back side elevation view thereof.

FIG. 5 right side elevation view thereof.

FIG. 6 is a left side elevation view thereof.

FIG. 7 is a top plan view thereof; and,

FIG. 8 is a bottom plan view thereof.

The features shown in dash-dot lines in the drawing depict portions of the fitness tracker. The dash dot dash lines define the bounds of the claimed design. The broken lines form no part of the claimed design.
